TWO-WAY BIT
 Grant Godfrey, Safford, Ariz.
 Application July 1, 1954, Serial No. 440,589
 1 Claim. (Cl. 255—64)

This invention relates to drill bits utilized in drilling holes in ore, coal and also utilized in drilling for oil, water and for exploratory examinations.

One important object of the invention is to provide a novel device of this character in which provision is made for the easy withdrawal of a bit in case it is necessary to perform this operation.

A second important object of the invention is to provide an integral device of this character which may be attached to the end of a drill rod and act both to drill inwardly or downwardly and to drill upwardly and outwardly.

A third important object of the invention is to provide a device of this character wherein the outward or upward movement of the bit may be facilitated by means provided on the upper side of the bit for clearing the path of withdrawal.

With the above and other objects in view, the invention consists in general of certain novel details of construction and combination of parts hereinafter fully described and illustrated in the accompanying drawings and particularly claimed.

In the accompanying drawings, like characters of reference indicate like parts in the several views and:

Figure 1 is a perspective view of the improved invention applied to the lower end of a drill rod.

Figure 2 is an enlarged perspective view of the present invention removed from the drill rod.

Figure 3 is a transverse section on the line 3—3 of Figure 4.

Figure 4 is a section on the line 4—4 of Figure 3. In the embodiment of the invention as herein shown there is provided a generally cylindrical structure having a cylindrical body portion 10. This body portion has a vertical passage 11 extending therethrough and at the upper end of this passage internal screw threads 12 are formed

2

so that the device may be attached to the lower end of the drill rod 13 by means of this threading.

Projecting outwardly from the lower end of the body 10 but integral therewith are lugs 14 and each of these lugs is slotted as at 15 to receive and frictionally retain a cutter 16 which, for some purposes may be of tool steel. In oil well drilling diamond cutters inset in steel shanks in conventional manner, may be employed.

At the upper end of the body there are provided similarly diverging lugs 17 having cutting edges 18.

Now by reference to Figure 4 it will be seen that the diameter X of the circle within which the cutters 16 revolve is somewhat less than the diameter of the circle in which the cutting edges 18 revolve.

In operation as the drill proceeds inwardly or downwardly a cylindrical bore of relatively great diameter is formed. However, the drill hole made in this manner may fill in slightly behind the full diameter intended to be drilled. In such a case when it is desired to withdraw the bit then the cutters 16 will have no power to remove any slight obstructions from the wall of the drill hole above the bit. The purpose of the cutting edges 18 is therefore to remove any of these slight obstructions and these cutting edges 18 may be made of the same material as the body 10 since the work they do is very slight but they will clear the way for ready withdrawal of the bit when desired. It has been found that as small a difference in diameter as one-twentieth of an inch is sufficient to ensure easy withdrawal of the bit when such becomes necessary or desirable.

What is claimed is:

As a new article of manufacture, a drill bit adapted to fit on the end of a drill rod and having a cylindrical socketed body portion, lugs spaced around and radiating outwardly from the lower end of said body, each of said lugs having a slotted cutter socket formed in its bottom face, said slots extending into said body, a cutter bit mounted in each of said slots, divergingly and upwardly extending lugs spaced around the upper end of said body and having cutting teeth formed on their upper edges of lesser diameter in revolution than the cutters carried by the first-mentioned lugs, said upwardly extending lugs being integral with said body.
